TAPE DISPENSING MACHINE

Walter F. Roper, Longmeadow, Mass.

Application January 21, 1947, Serial No. 723,294

5 Claims. (Cl. 164—43)

1

This invention relates to machines for dispensing adhesive tape in strip form and more particularly pressure sensitive tape which is drawn off a supply roll at a desired length and then severed.

An object of the invention is to provide a movable cutter and operating means arranged so that the hand of the operator in withdrawing the tape to a predetermined measured length, may be employed in the same motion to sever the tape, thus leaving the other hand of the operator free for the manipulation of the article which is to be taped.

A further object is to provide severing means for the tape which leaves a cut off end of the tape projecting from machine in such manner that it may be easily grasped by the operator for the next stroke of tape withdrawal.

The construction of the machine is of simple rugged and inexpensive character, and the moving parts are housed in a casing which provides a holder for the roll of tape and also serves as a guard for the cutting mechanism when not in use. Further objects and advantages of the invention will be apparent from the following more detailed description taken in connection with the accompanying drawings, in which,

Fig. 1 is a longitudinal section through the casing or main frame of the machine showing the interior moving parts thereof in side elevation. In this view the cutter is in its uppermost rest position.

Fig. 2 is a similar view showing the cutter in its lowermost position after the completion of a cut through the extended strip of tape;

Fig. 3 is a top plan view of the machine with the parts in the same position as in Fig. 2;

Fig. 4 is a bottom detail plan of the front portion of the cutter frame;

Fig. 5 is a detail section of the cutter frame along line 5—5 of Fig. 1; and

Fig. 6 is a front end view of the cutter frame in a slightly modified form so as to be adapted for the use of a conventional razor blade as the cutting element thereof.

Referring more particularly to the drawings, the main frame indicated at 1 is formed as a casing or housing for the machine, and comprises side walls 4 and 5 joined by transverse base webs 2 and 2' and an upper overhanging hood portion 3. As will become apparent, the operation of the machine in withdrawing and cutting off a length of tape is designed to be effected single handedly, and a frame or casing of the machine is preferably heavy enough to remain in position without the use of the operator's other hand.

2

The frame provides a holder for the supply roll of tape R by having each of the side walls 4 and 5 of said frame formed with a slotted seat such as at 6 within which the core shaft 7 of the supply roll is received in the usual manner. A table portion or platen 8 having a horizontal flat upper surface extends transversely of the frame between the side walls 4 and 5, and is located somewhat in advance of the periphery of the supply roll R, whereby the strip of tape indicated at T when drawn off the supply roll may be temporarily adhered to the upper surface of said platen, as indicated in Figs. 1 and 2. In these figures I have shown in dotted lines and indicated at F and F' the thumb and index finger of an operator grasping the forward end of the tape in withdrawing the same over said platen 8. It will be understood that the pressure sensitive tape will be caused to adhere to the platen 8 when brought to rest, as shown in Fig. 1, so that it will have no tendency to wind backwards onto the supply roll R after a length has been once withdrawn and located on said platen 8. In drawing out the tape to the position shown in Fig. 2, the fingers F, F' will first lift the tape off the platen 8 and then pull it forward to the length desired. Upon depression of fingers F, F' to the position in Fig. 2, the tape T will again stick to the platen 8 as shown.

In the preferable form of my machine, the drawn out tape is severed by the movable cutter blade 9 without the use of the ordinary coacting cutter bar. The single blade 9 will chop through the tape when the latter is held taut between the platen 8 and fingers of the operator as shown in Fig. 2. The transverse cut through the tape is made at a substantial distance in front of the platen 8 and the front portion 10 of the main frame 1 is contoured so as to leave an unobstructed free space or clearance in front of the platen 8 and below the cutter 9 when the latter is in its cutting position, as shown in said Fig. 2. The purpose of this arrangement is so that when the cut is completed and the cutter 9 is withdrawn to its rest position, as shown in Fig. 1, the tape strip struck down on platen 8 will have a protruding end extending in front of the platen 8 and above the clearance at 10, in position to be grasped between thumb and forefinger for the next withdrawal, as shown in said Fig. 1.

The cutter blade 9 is mounted on the front end 11 of a cutter frame having spaced parallel side arms 12 pivotally mounted on the main frame at fulcrum pins 13. The rear end of said cutter frame 12 is pivotally connected by link 14

to a bell crank 15, said latter member being pivoted at the shaft 16 to the main frame. The bell crank 15 is formed with an integral forwardly extending lever arm 17 which is adapted to be engaged by the operator's fingers and depressed for swinging the forward end of the cutter frame downwardly as will be apparent from the connections described. The lever 17 is positioned centrally of the main frame and is adapted to work up and down in a centrally located slot 10' provided in the front contoured wall 10 as shown in Fig. 3. A return spring 18 is connected at the pivot pin 19 at the lower end of the bell crank 15 and also to an anchorage 20 on the main frame, as shown, which spring normally tends to hold the parts in the position shown in Fig. 1. An adjustable stop gauge 21 is mounted on the lever arm 17 for being slidably adjusted to different positions thereon in measuring the amount of tape to be withdrawn for cutting. Notches 22 in the lever arm and the stud screw 23 in the stop gauge 21 serve to fasten the latter in any one of its several adjusted positions.

The cutter blade 9 is detachably fastened to the end 11 of frame 12 by suitable clamping bolts 25 and 26, and the lower cutting edge of said blade 9 is preferably serrated as shown in Fig. 5. Mounted on the cutter frame 12, adjacent to and at the rear of said cutter blade 9 is a resilient presser member 27 formed as a shaped wire bail with upper attaching legs 28 and 29 fastened beneath the aforesaid clamping bolts 25 and 26. The presser member has its lower horizontal and transversely extended portion 27 located slightly below the cutting edge of the knife 9 as clearly shown in Fig. 5. The function of this presser member 27 is clearly illustrated in Fig. 2. When the cutter blade 9 is lowered for a cutting operation the horizontal portion 27 of said presser member will engage the tape on the platen 8 slightly before the cutting edge of the blade engages said tape, and will hold the tape firmly against the platen during the cutting operation, the other end of the tape being held taut by the fingers of the operator, as shown in Fig. 2. Also as the cutter is withdrawn upwardly away from the tape, the spring action of member 27 will continue to hold the tape against the platen 8 for a brief period after the lower edge of the knife has been raised above the level of the tape. In this manner the pressure member acts as a stripping means for the tape in preventing the latter from following the upward movement of the cutter. A rubber bumper 30 is preferably carried by the end portion 11 of the cutter frame as shown in Fig. 2, to soften its return stroke against hood 3.

In the modification of the cutter frame shown in Fig. 6, the front end 11' thereof is provided with clamping bolts 25' and 26' set slightly at an angle to the horizontal and spaced apart for receiving the ordinary conventional razor blade 24 in the position shown. Since this type of blade is not serrated, it is preferable that it be positioned in an inclined direction with respect to the tape that will be cut thereby. The presser member 27 in this form of cutter is the same as that previously described and as shown has its lower horizontal portion slightly below the lower cutting edge of said razor blade 24.

The operation of the device may be briefly described as follows, assuming that an end of the tape strip has been pulled from the supply roll R and stuck down on the platen 8 as indicated in Fig. 1. The operator first grasps the

end of the tape and lifts it from the platen 8, and continues to pull thereon until his fingers strike against the stop gauge 21, as shown in Fig. 2. This will determine the length of tape to be cut. Then by a continuation of the same movement the operator depresses the stop gauge 21 and lever 17 so as to swing the cutter frame with its cutter down to cutting position as shown in Fig. 2. The desired length of tape has now been cut off and a new projected tape end has been stuck on the platen 8. As soon as the lever 17 is released, spring 18 will restore the parts to the position shown in Fig. 1 ready for the next operation. The clearance space in front of the platen provided by the cut away portion 10 of the main frame gives room for the operator's hand during the downward movement of lever 17 in cutting off the tape and also permits the operator to easily grasp the protruding end of the cut off tape which extends from platen 8. The centralized position of the forwardly extended hand lever 17 allows the entire operation of drawing out the tape and cutting it off to be performed single handedly in one continuous motion which is of great advantage in the rapid taping of packages. The hood portion 3 of the frame serves as a guard for the cutter 9 when in rest position as shown in Fig. 1.

What I claim is:

1. In a machine for dispensing adhesive tape in combination, a main frame, means for supporting a roll of tape therein adapted for manual withdrawal in strip form, a platen located in front of said roll against which the strip of tape is adapted to be adhered when withdrawn from the roll, said frame being formed with an unobstructed clearance space in front of said platen whereby the end of a tape strip adhered to said platen may be grasped by the operator for withdrawal from the roll, a movable cutter for severing said strip, said cutter being mounted to move to cut said tape at a point spaced forward from the end of said platen operating means for said cutter comprising a hand lever positioned forwardly and centrally of said frame directly in the path of the operator's hand when withdrawing the tape strip from said roll, whereby said operator's hand in so withdrawing the tape strip may in the same motion engage and operate said lever to cut the strip at the end of said withdrawing stroke.

2. In a machine for dispensing adhesive tape in combination, a main frame, means for supporting a roll of tape therein adapted for manual withdrawal in strip form, a platen located in front of said roll against which the strip of tape is adapted to be adhered when withdrawn from the roll, said frame being formed with an unobstructed clearance space in front of said platen whereby the end of a tape strip adhered to said platen may be grasped by the operator for withdrawal from the roll, a movable cutter for severing said strip, said cutter having its path of cutting movement in the unobstructed space at a substantial distance in front of said platen, operating means for said cutter comprising a hand lever pivoted to the main frame and positioned forwardly and centrally of said frame directly in the path of the operator's hand when withdrawing the tape strip from the roll, whereby said operator's hand in so withdrawing the tape strip may in the same motion engage and operate said lever to cut the strip at the end of said withdrawing stroke.

3. In a machine for dispensing adhesive tape in combination, a main frame, means for support-

ing a roll of tape therein adapted for manual withdrawal in strip form, a platen located in front of said roll against which the withdrawn strip is adapted to be adhered when withdrawn from the roll, said frame being formed with an unobstructed clearance space in front of said platen, whereby the end of a tape strip adhered to said platen may be grasped by the operator for withdrawal from the roll, means for severing said strip comprising a movable cutter mounted to move to cut said tape at a point spaced forward from the end of said platen, a presser member for holding the tape strip against said platen during the cutting action of the cutter, and a hand lever with connections for operating the cutter, said hand lever being pivoted on the frame and positioned forwardly and centrally of said frame directly in the path of the operator's hand when withdrawing the tape strip from the roll, so that said operator's hand in so withdrawing the tape strip may in the same motion engage and operate said lever to cut the strip at the end of said withdrawing stroke.

4. In a machine for dispensing adhesive tape in combination, a main frame, means for supporting a roll of tape therein adapted for manual withdrawal in strip form, a platen located in front of said roll against which the withdrawn tape strip is adapted to be adhered when withdrawn from the roll, said frame being formed with an unobstructed clearance space in front of said platen whereby the end of a tape strip adhered to said platen may be grasped by the operator for withdrawal from the roll, means for severing said strip comprising a cutter frame pivoted on said main frame, a cutter carried in said frame and mounted to cut said tape at a point spaced forward from the end of said platen, a spring acting presser member carried in said frame adjacent said cutter and arranged to hold the tape strip against said platen during the cutting action of the cutter, and a hand lever with connections for oper-

ating the cutter frame, said hand lever being positioned forwardly and centrally of said main frame and directly in the path of the operator's hand when withdrawing the tape strip from the roll, so that said operator's hand in so withdrawing the tape strip may in the same motion engage and operate said lever to cut the strip at the end of said withdrawing stroke.

5. In a machine for dispensing adhesive tape in combination, a main frame, means for supporting a roll of tape therein adapted for manual withdrawal in strip form, a platen located in front of said roll against which the strip of tape is adapted to be adhered when withdrawn from the roll, said frame being formed with an unobstructed clearance space in front of said platen whereby the end of a tape strip adhered to said platen may be grasped by the operator for withdrawal from the roll, means for severing said strip, comprising a cutter frame pivoted on said main frame, a cutter carried in said frame, a spring acting presser member carried in said frame adjacent said cutter and arranged to hold the tape strip against said platen during the cutting action of the cutter, said cutter being carried in the cutter frame so that its cutting action on the strip is in the unobstructed space and at a substantial distance in front of said platen so as to leave a cut end of the strip projecting forwardly from the platen to be grasped for a subsequent withdrawal, and a hand lever with connections for operating the cutter frame, said hand lever being positioned forwardly and centrally of said main frame and directly in the path of the operator's hand when withdrawing the tape strip from the roll, so that said operator's hand in so withdrawing the tape strip may in the same motion engage and operate said lever to cut the strip at the end of said withdrawing stroke.
